CARBURETOR ECONOMIZER MECHANISM

Robert H. Hieger, Detroit, Mich.

Application June 21, 1949, Serial No. 100,339

6 Claims. (Cl. 137—480)

1

This invention relates to carburetors for internal combustion engines, and more particularly to an economizer mechanism to enable the carburetor to supply fuel to the engine in increased quantity to increase the power thereof when needed.

Many commercial carburetors as now constructed include a device, usually referred to as an economizer or power jet, which includes a valve controlled by a piston or diaphragm subjected to the vacuum in the intake manifold to increase the rate of fuel supplied to the carburetor, and thereby enrich the fuel-air mixture, when the throttle is in or near its fully open position.

In the case of an economizer comprising a vacuum actuated piston, defective operation or failure of the economizer often results from corrosion of the cylinder walls, which develops friction and causes the economizer to operate haphazardly or not at all. Such friction may also be caused by misalignment of the piston in its cylinder, by grit or other foreign matter therein, or by other causes.

Defective operation of the economizer may also result from the return spring commonly used in such devices, and which may have too great or too small initial tension, causing the economizer to begin to function too soon, or too late, relative to a given decrease of vacuum in the manifold.

Defective operation of the economizer is difficult to detect, since commercial carburetors are so constructed that it is impossible, without disassembling the carburetor, to apply a measured amount of suction to the fuel outlet thereof and to the vacuum connection, and measure the resulting fuel flow. Also, if malfunctioning is found or suspected, it is difficult to remedy by means of ordinary shop tools.

An object of the present invention is to provide a carburetor comprising economizer mechanism having improved control or motor means which are not prone to get out of order, and wherein corrosion and also misalignment between the piston and its cylinder are avoided.

A further object of the invention is to provide an economizer motor which is usable in known types of carburetors in substitution for the corresponding mechanism originally supplied with the carburetor.

In the device of the present invention, the economizer motor unit comprises a piston and a cylinder of corrosion-resistant material such as brass, which may be substituted for the corresponding elements in a new or used carburetor. A piston rod is connected to the piston by a universal connection, so that the piston rod, which actuates the economizer valve, cannot

2

cause misalignment of the piston relative to its cylinder.

Further objects and advantages of the invention will be apparent from the following description, taken in connection with the appended drawing, in which:

Fig. 1 is a diagrammatic view of a carburetor and the fuel system thereof showing, on an enlarged scale, a device with the present invention incorporated therein.

Fig. 2 is an enlarged sectional view of the economizer motor and its associated parts, corresponding to a section taken on the line 2—2 of Fig. 1.

Fig. 3 is an enlarged plan view of one of the washers shown in Fig. 1.

Fig. 4 is an elevational view showing the economizer motor separately, i. e. in the form it is distributed to the trade as a separate article of manufacture for installation in the carburetors of cars already on the road.

It is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

The carburetor shown in the drawing is of the downdraft type commonly used with automobile engines, but may be of any known or suitable construction. It comprises a body 8 forming an induction passage which includes an air inlet 10, a main venturi 12, and a mixture outlet 14 designed to be connected to the intake manifold of an internal combustion engine, not shown. The induction passage is controlled in the usual manner by a manually operated throttle valve 16. Usually an air cleaner, such as is indicated fragmentarily at 18, is connected to the air inlet.

Fuel is supplied to the induction passage from a reservoir 20, which in the example shown is a float chamber having a float 22 therein, which actuates a fuel valve 24 controlling a fuel inlet 26 leading from any suitable source of supply. Thence the fuel flows through a passage 28 to the main fuel nozzle 32, which discharges into the main venturi 12 and is vented by an air bleed passage 33. In the example shown, a second venturi 34 is provided to form a discharge member for the main nozzle. A metering orifice 36 is provided in the passage 28, as is the usual practice, and an idling fuel passage (not shown) of any suitable construction, may lead from the passage 28 to discharge adjacent the edge of the throttle 16 when the same is in closed position. Suitable acceleration pump mechanism, as well

as check valves, vents and metering orifices may be provided, as known in the art.

The motor or control unit of the economizer comprises a cylinder 38 connected by a duct 40 to the induction passage of the carburetor posterior to the throttle 16 when the same is in closed position. A piston 42 in the cylinder is thus subjected to the manifold vacuum, which tends to move it upwardly. A piston rod 44 is carried by the piston 42 and extends downwardly therefrom, terminating in a shoe 46 which acts as a seat for a compression spring 48 which yieldingly urges the shoe downwardly against the force of the manifold vacuum. The arrangement thus far described is broadly old, but some of the elements thus far mentioned have novel features, as will appear hereinafter.

The valve unit of the economizer comprises a casing 50 mounted in the lower wall of the float chamber, and housing a spring-pressed valve member 52 which controls the flow of auxiliary fuel from the float chamber 20 through a restricted passage 54 to the fuel passage 28. Projecting upwardly from the valve 52 is a plunger 56 which is designed to be depressed by the shoe 46 when the piston 42 moves downwardly. This valve unit may be of known construction, an example being the unit shown in applicant's copending application Serial No. 83,687, filed March 26, 1949.

As indicated in Fig. 2, the cylinder 38 is formed in a portion 58 of the carburetor body which overlies the float chamber 20 and is usually formed integral with the air horn of the carburetor. Since the carburetor body is usually made of a zinc alloy which is subject to attack by various ingredients of commercial gasoline, the walls of the cylinder sometimes become corroded, causing the vacuum piston to "freeze" or otherwise malfunction. To avoid this, the cylinder, in the present invention, is provided with a cylindrical liner 60, of brass or similar non-corrodible material, and of such diameter as to receive the piston 42 in freely slideable relation.

A plug 62 is driven into the lower end of the liner sleeve 60, the plug being formed with a bore 63 to loosely receive the piston rod 44. The plug is provided with a flange 64 which may be tapered to insure a tight fit in the bore of the liner sleeve, and with a depending flange 66 which receives the upper end of spring 48.

The upper end of rod 44 is threaded, and engages the threaded bore of a sleeve nut 70 which seats loosely in a bore 72 in the upper end of piston 42. The bore 72 is connected to a smaller bore 74 in the piston 42 by a shoulder 76. Between the nut 70 and the shoulder 76 is positioned an annular resilient sealing member 78, of Buna N or the like, such as is disclosed in applicant's copending application Serial No. 83,688, filed March 26, 1949. Because the spring 48 exerts a constant downward force on the piston 42, the sealing member 78 is continuously under pressure, so that it is distorted in such manner as to provide an air tight seal against passage of air between bore 74 and bore 72, even though the nut 70 rocks relative to piston 42 as herein-after mentioned. The piston 42 may be provided with a peripheral groove 80, as is usual.

The piston 42 is provided with a depending annular flange 82 designed to contact the beveled upper edge of flange 64 when the piston is moved to its lowermost position by spring 48. In order to make it possible to vary the initial tension of spring 48, a plurality of U-washers 84 are in-

serted between the plug 62 and the upper end of the spring, and held in place by the flange 66. The U-washers may be removed, or more of them added, by depressing the upper end of the spring to a point below the flange 66.

Under certain conditions such as sudden deceleration of the vehicle on which the carburetor is mounted, liquid fuel may be splashed over the economizer motor unit in such a way as to fill 10 the space 86 between the piston 42 and the plug 62, and a quantity of such fuel may, unless prevented by means now to be described, be drawn by suction through the clearance space between sleeve 60 and piston 42 and thence through duct 40 to the engine, which will thus be caused to 15 misfire. In the present device, this is prevented by venting the space 86 so that substantially atmospheric pressure will at all times obtain therein. To this end, a duct 88 leads from the air inlet 10 to a cylindrical chamber 90 formed by reducing the outer diameter of sleeve 60 as indicated in Fig. 2. Thence the duct communicates with space 86 through a port 92 in the sleeve. This port is shown in Fig. 2 as being aligned with 20 duct 88, but obviously no such alignment is necessary. By reason of this construction, any fuel which may be present in space 86 is free to flow downwardly through bore 63 to the float chamber, and little be drawn through duct 40.

30 In the assembly of the parts making up the vacuum motor, spring 48 and plug 62 are placed on the piston rod 44, with any desired number of washers 84 interposed therebetween. The piston 42, and then the sealing member 78, are then 35 placed on the rod, the piston being held down against the resistance of spring 48 in order to permit the sealing member to be properly positioned. The nut 70 is then threaded into place on the rod 44 and the piston released, putting 40 the sealing member under pressure. The sleeve liner 60 is then driven into engagement with the plug 62. This assembly of parts may then be tested by the use of simple test equipment (not shown) to determine whether it functions properly under a given degree of manifold vacuum, and such adjustment as may be necessary is made by varying the number of washers 84. The cylinder 38 is then cleared of any foreign matter or 45 irregularities, and the assembly is driven into place in the cylinder, plug 62 being staked if desired to retain it in position.

In general, the fuel system of the carburetor just described functions in the same manner as the fuel systems in known types of carburetors. During normal operation of the carburetor the manifold vacuum is sufficiently high to hold piston 42 in its raised position, as shown in the drawing, so that valve 52 is closed and the entire supply of fuel to the nozzle 52 passes through metering orifice 36. But when the manifold vacuum drops, as when the throttle 16 is suddenly opened, spring 48 will move rod 44 downwardly to a position wherein the shoe 46 contacts the plunger 56, which will move the valve 52 off its seat and permit auxiliary fuel to flow from float chamber 20 past valve 52 and thence through passage 54 to the nozzle 32, enriching the mixture.

The economizer mechanism herein disclosed is resistant to corrosion, since all of its parts which are subject to sticking are formed of brass or other material not subject to corrosion, and clearances are sufficient to minimize the danger of such occurrence. In addition, such clearance is

provided between nut 42 and bore 72, and between rod 44 and bores 74 and 63, as to permit the nut 70 to tilt or rock slightly relative to the piston, and sealing member 78 by reason of its resilience permits such action while still maintaining its sealing action. The connection between rod 44 and piston 42 is a universal connection, and any misalignment between the rod and the sleeve 60 is thus automatically adjusted. If at any time there is a question whether the unit is functioning properly, or if it is desired to test the functioning of the motor, the entire motor unit may be removed from the carburetor. A measured degree of manifold vacuum may then be applied to the piston 42 to test the action thereof in moving rod 44. If the unit is found not to be functioning properly, the defective parts may be adjusted or replaced, and the unit replaced without disturbing its adjustment.

Although the invention has been described with reference to a particular embodiment thereof, it may be embodied in other forms within the skill of artisans in this art, and is not limited except in accordance with the terms of the following claims.

I claim:

1. A unit for actuating economizer valve of a carburetor having an air passage with a throttle provided therein and a float chamber and including a cylindrical bore at the top of said chamber, said bore opening into said chamber with its lower end, the upper end of said bore constantly communicating with said air passage on the downstream side of the throttle; said unit comprising a sleeve adapted to fit into said bore and to form a liner therein, a piston slidably fitted in said sleeve and having a through axial bore of different diameters to form a shoulder therein adapted to receive downward pressure, a piston rod having its upper end passing through said bore and engaging said shoulder for moving the piston downwardly and its lower end adapted to contact the economizer valve, and a plug surrounding the piston rod and secured to the lower end of said sleeve and adapted to be secured at the lower end of the sleeve-receiving bore for retaining the sleeve therein, said sleeve retaining in place, in the assembled condition of the unit, the piston, the plug and the piston rod.

2. The construction defined in claim 1, with a compression spring interposed between the lower end of the piston rod and the plug and adapted to maintain said rod, unless overcome by an exterior force, in its fully extended position; and a washer box on said plug adapted to receive a desired number of spring-adjusting washers.

3. A unit for actuating economizer valve of a carburetor having an air passage with a throttle provided therein and a float chamber and including a cylindrical bore at the top of said chamber, said bore opening into said chamber with its lower end, the upper end of said bore constantly communicating with said air passage on the downstream side of the throttle; said unit comprising a sleeve adapted to fit into said bore and to form a liner therein, a piston slidably fitted in said sleeve and having a through axial bore of at least two diameters to form a shoulder therein, a piston rod having its upper end passing through said bore and engaging said shoulder for moving the piston downwardly and its lower end adapted to contact the economizer valve, a sealing member interposed between the upper end of the piston rod and said shoulder and adapted, when the pis-

ton rod exerts pressure on said shoulder, to seal the axial bore in said piston to flow of fluid.

4. A unit for actuating economizer valve of a carburetor having an air passage with a throttle provided therein and a float chamber and including a cylindrical bore at the top of said chamber, said bore opening into said chamber with its lower end, the upper end of said bore constantly communicating with said air passage on the downstream side of the throttle; said unit comprising a sleeve adapted to fit into said bore and to form a liner therein, a piston slidably fitted in said sleeve, and having a through axial bore of two diameters to form a shoulder therein, a piston rod having its upper end passing through said bore and engaging said shoulder for moving the piston downwardly and its lower end adapted to contact the economizer valve, a sealing member interposed between the upper end of the piston rod and said shoulder and adapted, when the piston rod exerts pressure on said shoulder, to seal the axial bore in said piston to flow of fluid, said piston rod having diameter effecting predetermined clearance between the rod and the piston as well as the plug, providing for such sidewise movement of the rod in the sleeve as may be caused in operation by the angular misalignment of the rod.

5. A unit for actuating economizer valve of a carburetor having an air passage with a throttle provided therein and a float chamber and including a cylindrical bore at the top of said chamber, said bore opening into said chamber with its lower end, the upper end of said bore constantly communicating with said air passage on the downstream side of the throttle; said unit including a piston adapted to operate within said bore, said piston having a through axial bore of different diameters to form a shoulder therein adapted to receive downward pressure, a piston rod having one end arranged within the bore of the piston with a predetermined clearance and extending beyond said shoulder, a member provided on the end of said piston rod and adapted, when a downward force is exerted on the rod, to exert pressure on said shoulder, and a sealing member interposed between said member and said shoulder and adapted to seal said clearance when the piston rod exerts through its end member pressure toward said shoulder.

6. The construction defined in claim 5, with said sealing member being made of a material having elasticity ensuring that the member on the end of the piston rod exerts sealing pressure on the entire sealing member even when the piston rod is in the position of the maximum axial misalignment determined by the clearance.
